LIQUID APPLICATOR

David Mayor Gordon, Flushing, N. Y.

Application March 14, 1951, Serial No. 215,530

4 Claims. (Cl. 15—140.3)

1

This invention relates to new and useful improvements in combined bottle caps and liquid applicators.

One object of the invention is the provision of an inexpensively manufactured bottle cap and liquid applicator that is somewhat flexible and thus is not easily broken.

Another object of the invention is the provision in such a device of simple and effective means for increasing the amount of liquid that adheres thereto.

Still another object of the invention is the provision in such a device of a liquid reservoir employable at will.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a simplified form of the invention.

Fig. 2 is a sectional view on line 2—2 of Fig. 1.

Fig. 3 is a perspective view of a slightly modified form of the invention.

Fig. 4 is a perspective view of another form of the invention.

Fig. 5 is a sectional view on line 5—5 of Fig. 4.

Fig. 6 is a fragmentary view of a modified form of applicator tip.

Fig. 7 is an enlarged end view of the applicator tip of Fig. 6.

Fig. 8 is a fragmentary side elevational view of an applicator tip having a liquid retaining reservoir therein.

Fig. 9 is a view similar to Fig. 8 but of the opposite side of said tip.

Fig. 10 is an enlarged sectional view on line 10—10 of Fig. 9.

Fig. 11 is a sectional view on line 11—11 of Fig. 10.

Referring first to Figs. 1 and 2, wherein a simplified form of the invention is illustrated, the reference numeral 10 indicates a frusto-conical bottle stopper having a slender tapering rod 11 projecting from the narrower end thereof. Preferably the rod and the stopper are formed integrally of a plastic material that is sufficiently flexible to allow of a slight compression of the stopper and some bending of the rod.

The construction is such that the stopper 10 may be wedged in the neck of a bottle to seal the latter and said rod may be used as an applicator for liquid contained within the bottle.

2

Referring to Fig. 3 wherein like parts are given the same reference numerals as above with a prime added, the stopper 10' may be provided at its wider end with an annular flange 12 for engaging the lip of a bottle neck. Further, the tip of rod 11' is provided with a knob 13 adapted to increase the amount of liquid that adheres to said tip and is thus available for application. Preferably the diameter of the knob 13 does not exceed that of the thicker end of rod 11', it being financially desirous to mold the device with a suitably tapered rod which is later necked down to form the knob 13.

A modified form of the invention is illustrated in Figs. 4 and 5 and includes a bottle cap 14 threaded internally for engagement on a bottle neck, and, integral therewith, a tapering applicator rod 15. Preferably the device is formed of a plastic material of the type indicated above. In order to increase the amount of liquid carryable by the rod 15 the tip thereof is provided with a diametral groove 16 in which a quantity of said liquid lodges.

Referring now to Figs. 6 and 7 wherein an arrangement for increasing the liquid carrying capacity of any of the described applicator rods is illustrated, the reference numeral 17 indicates a tapering applicator rod having a flattened knob 18 at its narrow end. As mentioned above, knob 18 preferably is of a lesser diameter than the thicker end of rod 17. In the flattened face of knob 18 there is provided a plurality of parallel shallow grooves 20 in each of which a small quantity of the liquid to be applied lodges. Thus the liquid carrying capacity of the rod is substantially increased.

Referring to Figs. 8-11 there is illustrated a tapering applicator rod 21 having at the end thereof a knob 22 which is split diametrically to form a narrow channel 23 that widens quickly as it approaches the end of the knob to form oppositely disposed cam faces 24 by which the channel can be spread open. At its other end channel 23 opens into a cavity 25 which in form is a diametral bore having either end substantially stoppered by a flap 26 which is formed by continuing the channel forming slit beyond the end of the channel in a circular path as indicated at 27. Preferably the slits 27 curve in opposite directions so that the anchored portions of the flaps 26 are substantially diametrically opposed.

The construction is such that the slits 27 are sufficiently open to allow a quantity of liquid to enter cavity 25 through channel 23 when the applicator is immersed in said liquid. Further, the liquid entering said cavity is held therein by

the flaps 26 and the narrowness of channel 23 until the latter is spread open by forcing the cam faces 24 against the surface on which it is desired to deposit the liquid.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A combined bottle stopper and liquid applicator which comprises a bottle sealing member having a tapering applicator rod projecting from one end thereof, said sealing member and rod being formed integrally of a plastic material that is sufficiently flexible to permit some bending of the rod, and said rod having at its tapered end a knob split diametrically to form a narrow channel which at its outer end widens sharply to form oppositely disposed cam faces by which the channel can be spread open, a diametral bore in the rod being located at the inner end of the channel, said bore having its ends partially stoppered by wall-like flaps formed by continuing the channel forming slit in a circular path.

2. A combined bottle stopper and liquid applicator which comprises a frusto-conical stopper having a tapering applicator rod projecting from the narrower end thereof, said stopper and said rod being formed integrally of a plastic material that is sufficiently flexible to permit some bending of the applicator rod, and said rod having at its tapered end a knob split diametrically to form a narrow channel which at its outer end widens sharply to form oppositely disposed cam faces by which the channel can be spread open, a diametral bore in the rod being located at the inner end of the channel, said bore having its ends partially stoppered by wall-like flaps formed by continuing the channel forming slit in a circular path.

3. A combined bottle stopper and liquid appli-

cator which comprises a bottle sealing member having a tapering applicator rod projecting from one end thereof, said sealing member and rod being formed integrally of a plastic material that is sufficiently flexible to permit some bending of the rod, and said rod having at its tapered end a knob split diametrically to form a narrow channel which at its outer end widens sharply to form oppositely disposed cam faces by which the channel can be spread open, a diametral bore in the rod being located at the inner end of the channel, said bore having its ends partially stoppered by wall-like flaps formed by continuing the channel forming slit in a circular path, said flaps and the narrowness of the channel serving to retain in said bore a quantity of liquid which is released by spreading the channel.

4. A combined bottle stopper and liquid applicator which comprises a frusto-conical stopper having a tapering applicator rod projecting from the narrower end thereof, said stopper and said rod being formed integrally of a plastic material that is sufficiently flexible to permit some bending of the applicator rod, and said rod having at its tapered end a knob split diametrically to form a narrow channel which at its outer end widens sharply to form oppositely disposed cam faces by which the channel can be spread open, a diametral bore in the rod being located at the inner end of the channel, said bore having its ends partially stoppered by wall-like flaps formed by continuing the channel forming slit in a circular path, said flaps and the narrowness of the channel serving to retain in said bore a quantity of liquid which is released by spreading the channel.
